AUXILIARY GRATE FOR HALF-TANK
ICING

Charles W. Hiles, Houston, Tex.

Application December 24, 1935, Serial No. 56,022

6 Claims. (Cl. 62—19)

The present invention relates to a movable auxiliary grate for permitting the partial icing of a refrigerator car.

In the use of refrigerator cars, it is frequently desirable or expedient to only partially fill the ice tanks with ice. When so doing, it is economical to keep the partial load of ice in the upper portion of the ice tank and against the bulkhead separating the tank from the lading compartment of the car.

The objects of the present invention are to provide an auxiliary grate, built into the ice tank in such a manner as to be quickly movable into position to support a partial load of ice, and which, when not so used, can be swung back against the end of the car to form one wall of the full sized tank; to provide an auxiliary grate in such a position as to support its partial load of ice in the upper portion of the ice tank and against the bulkhead wall; and to provide an auxiliary grate which can be shifted from operative position to inoperative position even when supporting a partial load of ice. Other objects and advantages of the invention will become apparent from the following specification, which should be read with the understanding that the form, construction and arrangement of the several parts herein shown and described may be varied, within the limits of the claims hereto appended, without departing from the spirit of the invention.

Reference will be made to the accompanying drawings, wherein

Fig. 1 is a vertical transverse section showing a portion of the ice tank at the end of a refrigerator car, being taken on the line 1—1 of Fig. 2.

Fig. 2 is a vertical longitudinal section taken on the line 2—2 of Fig. 1, showing the auxiliary grate in inoperative position, i. e. for full-tank icing.

Fig. 3 is a section similar to Fig. 2 showing the auxiliary grate in operative position for half-tank icing.

Fig. 4 is a horizontal section taken on the line 4—4 of Fig. 1, showing the auxiliary grate in inoperative position.

Fig. 5 is a broken enlarged elevation of the locking bolt shown in Figs. 2 and 3.

In the drawings, the reference numeral 6 designates the end wall of a refrigerator car, 7 is a side wall, 8 is the floor, and 9 is the roof. A hatch 10 in said roof gives access to the ice tank 11. The usual bulkhead 12 separates the ice tank from the lading compartment 13 of the car. In the lower portion of the ice tank is a permanent

grate 14 for supporting a full tank of ice. So much is the usual construction of a refrigerator car.

My improvement consists primarily of an auxiliary grate 15, which, when not in use to support a partial load of ice, occupies a vertical position adjacent the end wall 6 of the car, as shown in Fig. 2. In this position, the auxiliary grate 15 forms the inner wall or lining of the ice tank, there being no other lining necessary inside the end wall 6. The side wall 7 is provided with the usual permanent lining, shown as a screen 16 in Fig. 1. The bulkhead 12 may also be provided with a suitable lining, as usual, although it has been omitted from the drawings to avoid confusion.

The auxiliary grate 15, which extends the entire width and height of the ice tank, is preferably formed in sections, as shown in Fig. 1, for convenience in assembling, each section consisting of a rectangular steel frame 17 surrounding a screen panel 18. The sections, however, are all rigidly connected together, by bolts and spacers 19, so that the entire grate moves as a unit. Vertical angle bars 20, Fig. 4, are secured to the back of the grate sections, the projecting flanges of said angle bars abutting against the end wall of the car to maintain air spaces between said wall and the screen panels 18.

The sections of the auxiliary grate 15 are provided with horizontal hinge pins 21, Figs. 1 and 2, which extend between the flanges of the angle bars 20 at the upper ends thereof. The hinge pins 21 ride in vertical slots 22, Fig. 2, formed in brackets 23 secured to the end wall 6 of the car. The bottom of the auxiliary grate is provided with rollers 24, Figs. 1 and 2, which travel upon the permanent grate 14, thereby supporting the weight of said auxiliary grate, and permitting it to be shifted easily from the vertical position shown in Fig. 2 to the inclined position shown in Fig. 3. In this inclined position, the grate 15 extends from the upper rear portion of the ice tank diagonally to the lower front portion, and supports a load of ice (not shown) in the triangular space above it, equal to approximately half the capacity of the tank. The hinge pins 21 rest against the bottoms of the slots 22 to support the upper end of the grate 15, and the rollers 24 rest on the permanent grate 14 against the bulkhead 12 to support its lower end.

The auxiliary grate 15 is held in its vertical position, against the end wall 6, by a suitable latch, preferably a slide bolt 25 which engages an apertured lug 26 extending from said end wall, 55

as shown in Figs. 1, 2 and 3. In its inclined, or half-tank icing position, the grate 15 is locked by vertically slidable bolts 27, Figs. 3, 4 and 5, mounted upon the bulkhead 12, the lower ends 5 of said bolts entering keeper lugs 28 and passing through eyes in the ends of links 29 pivotally secured to said grate at 30. When released by raising the bolts 27, the links drop down into the spaces between the grate sections, as shown in 10 Figs. 1 and 2. A grab bar 31, Fig. 1, is preferably provided in at least one of the grate sections, to facilitate pulling said grate forward to its inclined position.

When the auxiliary grate is in its vertical position, it presents no interference or restriction to the full icing of the tank, as clearly shown in 15 Figs. 2 and 4, nor does it reduce the size of the tank, because it forms the rear wall thereof, taking the place of the usual screen lining.

20 When it is desired to shift the grate to half-tank icing position, the operator descends into the tank 11, or reaches down through the hatch 10 with a hooked bar (not shown), releases the latch bolt 25, and pulls the lower end of the grate 15 forwardly to bring it to its inclined position, the weight of the grate itself assisting such movement. The links 29 are then lifted and locked with the bolts 27, and the tank is ready for half-icing. It is to be noted that, in this position, the 25 half load of ice is held against the bulkhead 12, and the major portion of it is in the upper region of the tank, this being the most effective and economical position for a partial load of ice.

When it is desired to restore the tank to full-icing capacity, the operator reaches in through 30 the hatch and lifts the locking bolts 27. If sufficient ice is left between the diagonal grate 15 and the bulkhead, its weight will force said grate back to vertical position against the end 35 wall 6, the ice dropping down onto the permanent grate 14. If ice is not present, the auxiliary grate 15 can be pushed back with a bar manipulated through the hatch. Thus the restoration of the tank to full icing capacity can be accomplished 40 quickly, even though it may contain some ice remaining from its previous partial load.

I claim:

1. In a refrigerator car having an ice tank and a lading compartment, a bulkhead separating 45 said tank from said compartment, a substantially horizontal ice grate in the lower portion of said tank, and an auxiliary grate mounted in an inclined position within said tank, the lower edge of said auxiliary grate resting upon said horizontal 50 grate adjacent said bulkhead and its upper edge being supported adjacent the opposite wall in the upper region of the tank, said auxiliary grate being movable from said inclined position to a vertical position adjacent one wall of said tank.

2. In a refrigerator car having an ice tank and a lading compartment, a bulkhead separating said tank from said compartment, a substantially horizontal ice grate in the lower portion 55 of said tank, an auxiliary grate mounted in an inclined position within said tank, the lower edge of said auxiliary grate resting upon said horizontal 60 grate adjacent said bulkhead and its upper edge being supported adjacent the opposite wall in the upper region of the tank, said auxiliary 65 grate being movable from said inclined position to a vertical position adjacent one wall of said tank, and vertical flanges projecting from the back of the auxiliary grate, said flanges spacing 70 said grate from said end wall to provide air pas-

sages therebetween, whereby said grate when in its vertical position forms a portion of the wall of said tank.

3. In a refrigerator car having an ice tank and a lading compartment, a bulkhead separating 5 said tank from said compartment, a substantially horizontal ice grate in the lower portion of said tank, an auxiliary grate mounted in an inclined position within said tank, the lower edge of said auxiliary grate resting upon said horizontal 10 grate adjacent said bulkhead and its upper edge being supported adjacent the opposite wall in the upper region of the tank, said auxiliary 15 grate being movable from said inclined position to a vertical position adjacent one wall of said tank, and a roller mounted upon the lower edge of the auxiliary grate to travel upon the horizontal grate during the movement of said auxiliary grate.

4. In a refrigerator car having an ice tank and 20 a lading compartment, a bulkhead separating said tank from said compartment, a substantially horizontal ice grate in the lower portion of said tank, an auxiliary grate mounted in an inclined position within said tank, the lower edge 25 of said auxiliary grate resting upon said horizontal grate adjacent said bulkhead and its upper edge being supported adjacent the opposite wall in the upper region of the tank, said auxiliary 30 grate being movable from said inclined position to a vertical position adjacent one wall of said tank, and a sliding and pivotal connection 35 between the upper edge of the auxiliary grate and the adjacent wall, whereby said upper edge is permitted to move up and down while being held adjacent said wall during the movement 40 of said grate between its inclined and vertical positions.

5. In a refrigerator car having an ice tank provided with a plurality of lined walls and an 45 unlined wall, an ice supporting grate in the lower portion of said tank, and an auxiliary grate within said tank above the first mentioned grate, said auxiliary grate being movable from an inclined position extending from the lower portion 50 of the tank at one side to its upper portion at the opposite side, to a vertical position adjacent the unlined wall of said tank, whereby when said auxiliary grate is in its inclined position it can support a partial load of ice, and when it is in 55 its vertical position it forms a lining for said unlined wall, permitting a full load of ice to be carried.

6. In a refrigerator car having an ice tank and a hatch in its roof giving access thereto, an auxiliary grate mounted in an inclined position within said tank, extending from the lower portion thereof at one side to the upper portion at the other side to support a partial load of ice, said 60 grate being movable to a vertical position adjacent one wall of the tank to permit full icing thereof, locking means for holding said grate in said inclined position, and a member for operating said locking means, said member extending upwardly and being accessible through said 65 hatch.

7. In a refrigerator car having an ice tank and a lading compartment, a bulkhead forming one wall of said tank and separating it from said compartment, and an ice supporting grate in said 70 tank mounted in an inclined position with one edge adjacent said bulkhead in the lower portion of said tank, and its opposite edge adjacent the wall opposite said bulkhead in the upper portion of said tank, said grate being movable from said 75

2,081,332

inclined position to a vertical position adjacent one of said walls.

8. In a refrigerator car having an ice compartment, an ice supporting grate mounted in an inclined position in said compartment extending diagonally from the lower portion of one wall thereof to the upper portion of the opposite wall,

said grate being movable to a vertical position extending from the bottom to the top of said compartment adjacent one of said walls, and means for spacing said grate, when in said vertical position, from the adjacent wall to maintain 5 an air flue therebetween.

CHARLES W. HILES.
